END POINT MOISTURE CONTENT CONTROL APPARATUS FOR SAND

Harry W. Dietert and Randolph L. Dietert, Detroit, Mich., assignors to Harry W. Dietert Company, Detroit, Mich., a corporation of Michigan

Application July 29, 1957, Serial No. 674,822

6 Claims. (Cl. 22—89)

The present invention relates to end point moisture content control for sand.

It is an object of the present invention to provide an automatic system for controlling the addition of water to foundry sand during the milling in accordance with the increasing moisture content due to addition of water and preferably also the temperature of the mixture, characterized in that the measurement of moisture content and/or temperature and the transmission of these measurements into the control system is accomplished without any moving parts.

It is a further object of the present invention to provide a system as described in the preceding paragraph in which both moisture content and/or temperature measurements are taken as variable capacitances which are transmitted to a control circuit for a vacuum tube.

It is a further object of the present invention to provide an automatic system for adding water to sand in a mill, mixing the sand and water, sensing the moisture content of the sand, and preventing termination of the addition of water which might result from sensing of a moist sample of sand in the mill while the average moisture content is below that required.

More specifically, it is an object of the present invention to provide a system for adding water to sand in a mill, the system including a moisture sensitive element adapted to measure moisture content of sand at a particular point in the mill, and including means for preventing accidental termination of addition of water which might result from passage of a small volume of moist sand across the moisture sensing element.

Still more specifically, it is an object of the present invention to provide apparatus for sensing moisture content of sand in the mill as water is added thereto, means for continuing the addition of water until the moisture content reaches a predetermined fraction of the required final moisture content, means for reducing the rate of flow of water into the mill until a second higher value of moisture content is sensed, and means for thereafter repeatedly sensing moisture content at intervals to provide for addition of water if any of the subsequent moisture sensing operations results in a sensing of less than required moisture content.

It is a further object of the present invention to provide end point control for sand moisture in a mill including a moisture probe located in a wall of the mill, mixing members in the mill movable over the moisture probe and adapted to compact a specimen of sand against the probe, a scraper movable over the probe following each compacting operation effective to remove compacted sand from the surface of the probe, said probe including a metal button having a surface exposed at a surface of the wall of the mill, and a surrounding bushing formed of tetrafluoroethylene available under the trade name "Teflon."

It is a further object of the present invention to provide a moisture probe comprising a tube terminating at one end in a conical seat, an annular bushing received

2

in said one end of said seat and having an outwardly enlarged internally and externally conical portion engaged in said seat, a probe button formed of metal received in said bushing having an outwardly enlarged 5 conical end portion seated in the internal conical portion of said bushing.

It is a further object of the present invention to provide a probe of the character described in the preceding paragraph including resilient means for urging said probe button firmly against the seat.

Other objects and features of the invention will become apparent as the description proceeds, especially when taken in conjunction with the accompanying drawings, illustrating a preferred embodiment of the invention, wherein:

Figure 1 is a combined schematic view and wiring diagram of the end point moisture content control for sand.

Figure 2 is a longitudinal sectional view through the moisture probe.

Figure 3 is a longitudinal section through the thimble element of the probe.

Referring now to the drawings, the sand mill 10 is adapted to receive sand from a plurality of hoppers 12 and water is added to the sand through valve means later to be described, but the addition directly to the mill is through sprinklers 14 connected to a receptacle 16 which receives water from a discharge pipe 18. The sprinklers 14 are suitably supported as for example by 30 a part 20, for rotation with the rollers 22.

In Figure 1, which is diagrammatic in character, the sprinkler heads are shown as located above the rollers 22 but in practice they are preferably circumferentially spaced therefrom.

The sand mill 10 is of the type including the relatively heavy rollers 22 previously referred to and in addition and rotatable therewith, there is provided a plow 24 having a leading edge spaced only slightly above the bottom wall of the mill and adapted to scrape the sand therefrom after it has been compacted by the rollers 22. In practice the leading edge of the plow 24 may be spaced slightly upwardly from the bottom wall of the mill, as for example approximately $\frac{1}{4}$ of an inch.

Located in the bottom wall of the mill 10 is a moisture probe 26, details of which will be presently described. The moisture probe is preferably located directly under the path of the rollers 22 so that as the rollers pass over the moisture probe, they compact the sand against the moisture probe to give a reading the value of 50 which is determined simultaneously by the moisture content of the sand and its state of compression.

Due to the specific nature of the moisture probe, the succeeding passage of the plow 24 thereover is effective to remove all sand previously compacted against the face 55 of the probe. The moisture probe is adapted to sense a capacity which is dependent on the moisture content of the sand.

Means are provided for sensing the temperature of the moist sand in the mill. This means comprises a 60 temperature sensitive ceramic condenser 38 exposed in a wall of the mill to the moist sand. The condenser is available on the open market and no claim to details of this condenser apart from the combination is made herein.

Opposite sides of the capacitor or condenser 38 are connected to terminals X and Y of the moisture sensitive bridge later to be described.

The moisture probe 26 is connected by lines 50 and 52 to a moisture measuring bridge indicated at 53, which 70 is a measuring instrument identified as Tektor unit #101, manufactured and sold by the Fielding Instrument Division of the Robertshaw-Fulton Control Company. The

line 50 is grounded as indicated at 54, and line 52 is connected through a high capacity capacitor 56 to instrument connector X. Also connected in line 52 is a variable trim capacitor 58 effective to make the required adjustments in the unit. The variable capacitor 38, actuated in accordance with the temperature of the mixture in the mill is connected to the instrument connection X and to a second instrument connection Y. The instrument connection X is connected to the grid of a vacuum tube, for example a 6SN7 tube, connected as shown to have its output applied to a relay coil M which actuates switch contact arms M1 and M2. Also connected to the instrument connections are an adjustable first point capacitor 62 and an adjustable end point capacitor 64. The end point capacitor 64 is connected in parallel with a high capacity, as for example 2000 m.m.f., fixed capacitor 66, by normally closed contacts R7a of a relay R7 later to be described.

Described in general terms, the system operates as follows: The operator pushes a button which starts rotation of the mixing apparatus, the sand being dumped in at this time or subsequently. Inasmuch as sand may be dumped in from one of a plurality of hoppers, it is desirable to effect substantial mixing of the sand before any attempt is made to determine its moisture.

After a predetermined interval of mixing, operation of the moisture control device is initiated. A timer is started which will insure rechecking the moisture content after a predetermined interval even though the instrument may previously have indicated sufficient moisture. This is because of the possibility of a false reading and rechecking after a predetermined interval will insure continued operation of the instrument until the moisture content is adequate.

During operation of the instrument, the first point valve Va and the end point valve Vb are opened and water is supplied to the sand while it continues to be mixed. Inasmuch as the mixing operation comprises the passing of the rollers 22 over the moisture probe 26, followed almost immediately by passage of the plow 24, it will be appreciated that even when the sand reaches the required moisture content, this correct moisture content will be indicated only at intervals determined by the passage of the rollers 22 over the probe. After the scraper or plow 24 has passed over the probe, the sensing system will indicate a moisture deficiency until the succeeding sample of moist sand is compressed against the probe.

At this time it is desired to add the water rapidly to bring the moisture content up to approximately but definitely below the desired value. Accordingly, at this time control of the instrument is by the first point capacitor 62 and temperature compensating capacitor 38. Eventually, the instrument senses the proper moisture content for a brief interval and the system is arranged at this time to close the large capacity first point valve Va and to shift control of the instrument to the combination of the three capacitances, the end point capacitance 64, the temperature compensating capacitance 38, and the modifying capacitance 66. Capacitance 66 is a large value capacity, for example 2000 micro-micro-farads, which is sufficient to stop the 6SN7 tube from oscillating and in turn de-energizes relay M and causing M2b to make contact at M2c which completes the circuit to contacts R5a to energize relays R7 and R4, thus taking capacitance 66 out of the circuit at contacts R7a for the remaining part of the cycle, leaving the control of the instrument to the sum of the end point capacitance 64 and temperature compensating capacitance 38. Thereafter, water continues to be added to the mill at a reduced rate by the end point valve Vb until the first indication of the ultimate desired moisture is obtained. It is recognized however, that this may be a false indication resulting from sensing the moisture content of a small specimen not indicative of the true average moisture content of the sand. Ac-

cordingly, means are provided at this time to close the end point valve while the mixing of the sand continues. During the following interval moisture readings are taken periodically as the rollers 22 pass over the sand probe. 5 So long as these moisture readings all indicate sufficient moisture the valve Vb remains closed. A timing means is provided to operate over for example three seconds, which prevents opening of the end point valve during the brief intervals between successive sensing operations. 10 For example, resensing may occur every two seconds and the timer may be set to time out in three seconds. At the end of two seconds if the sensing of moisture indicates sufficient moisture, the timer is reset to zero.

On the other hand, if during this rechecking interval a 15 moisture sensing operation indicates insufficient moisture, the moisture valve opens and remains open until a second sensing of adequate moisture. This operation continues for an interval determined by an additional timer which operates to terminate the rechecking operation and to 20 maintain the end point valve Vb closed, thus ending the cycle.

When the system is set in operation, the capacities of the moisture probe 26, the trim capacitor 58, the temperature responsive capacitor 38, and the first point 25 capacitor 62, are all connected to the instrument connections X, Y. When sufficient moisture has been added to the mill 10 to increase the capacity of the moisture probe 26 to a predetermined value, the 6SN7 tube will oscillate and will energize the relay coil M.

30 Oscillation of the 6SN7 tube is dependent upon the algebraic sum of the capacities connected to the instrument connections X and Y.

The addition of water through the discharge pipe 18 is 35 through a first point valve Va which is air controlled and the supply of air controlling the valve is in turn controlled by a winding Va1 which will subsequently be described. At the same time an end point valve Vb is provided also controlled by air, which in turn is controlled by solenoid Vb1. The arrangement is such that 40 when the solenoids Va1 and Vb1 are energized the corresponding valves are closed. The valves of course are open when the respective windings are de-energized.

The operation of the complete system will be described 45 in connection with the illustrated circuit, which will be described to the extent necessary to understand the system. A 110-volt power line indicated at 70 is connected to the control circuit through a manual control switch 71. The control circuit includes the transformer Ta which is energized whenever the manual switch 71 50 is closed and which in turn supplies the primary of a second transformer Tb having the 250-volt, 6.3-volt secondary windings illustrated in the Tektor unit.

In operation sand is dumped into the mill from the 55 hoppers 12 without regard to the moisture content of the sand in the hoppers. For example, the sand in one of the hoppers may be substantially moist and this sand may be dumped into the mill first so that it immediately contacts the moisture probe 26. The drier sand from the other hopper is at the top of the mill and is ineffective 60 on the moisture probe. In order to insure that this condition does not prevent the required addition of moisture, the circuit includes timing means operable to provide a cycling of the control system after a predetermined interval irrespective of whether or not the instrument cut off the supply of water during the first timed interval. This means comprises a timer resistance T1 having a 65 switch arm T1a associated therewith. The switch arm T1a may for example be in the form of a bi-metallic contact member which is normally open and which closes after the resistance T1 has been energized for a substantial period, as for example 15 seconds. Closure of the manual switch 71 starts heating resistance element T1 through contact R2a, the contact being in the illustrated position when the relay R2 is de-energized.

70 After the predetermined initial period, as for ex-

ample 15 seconds, has elapsed, the switch arm **T1a** closes energizing relay **R2** and moving relay arm **R2a** to its lower position establishing a holding circuit through the relay **R2** and de-energizing timer **T1**. The relay **R2** remains energized for the remainder of the complete cycle. In addition, energization of relay **R2** shifts relay arm **R2b** to the left energizing relay **R1**. Energization of relay **R1** shifts relay arm **R1a** to the left establishing a connection to the lower portion of the circuit through jumper line **80**, around arm **R2b**, which remains to the left, holding relay **R1** in.

During the interval measured by the timer **T1** it may be possible for sufficient water to have been added to the sand and mixed therewith, in which case the operation should be terminated. In other cases a false signal may have resulted in closure of the valves **Va** and **Vb**. When the timer **T1** times out switch arm **R2b** moves clockwise, thus momentarily breaking the circuit to the lower portion of the system. When the switch arm **R2b** is in its lowermost or clockwise rotated position it energizes relay **R1** which closes a circuit through switch arm **R1a**, thus re-energizing the lower portion of the circuit. The interval between energization of relay **R2** and energization of relay **R1** is substantial and all circuits completed through portions of the wiring diagram below relay **R1** in the figure are de-energized so that all holding circuits drop out. When the switch arm **R1a** completes its movement all circuits are again re-energized and checking of the moisture of the sand is resumed. If in fact, the moisture content of the sand is sufficient this recheck results in quick cycling of the instrument to close valves **Va** and **Vb** and they will remain closed for an interval determined by energization of a timer **ES2** later to be described, which finally completes the cycle.

The operation of the system during the interval controlled by the timer **T1** is exactly the same as it would be if the timer were omitted. The function of the timer is to restart the complete cycle after a predetermined interval so that additional water can be added if the operation of the system was terminated as a result of a false signal during the first timed interval. A second important function of the initial timing period depends upon the following: It may happen that during the initial timing period a first signal is received from the moisture measuring unit which will have the effect of closing the large capacity valve **Va** and leaving additional water to be supplied through the relatively smaller end point valve **Vb**. If the false signal was the result of a small quantity of very moist sand happening to contact the moisture probe, a large volume of water may in fact be required to bring the average moisture content of the sand to the required value. During the initial interval timed by the timer **T1**, water will be added through the small capacity valve **Vb**. However, when the timer **T1** times out the control circuit is completely de-energized and re-energized, thus starting afresh with the large capacity valve **Va** open and the valve will remain open until the measuring unit makes the first signal indicating adequate moisture, which signal is sometimes referred to herein as a wet signal.

Assuming that insufficient water has been added to the sand, the rollers and plows continue to rotate, and water is now added to the mill through the valves **Va** and **Vb**. The solenoid **Va1** of the first water valve **Va** is energized through lines **72**, **74**, **76**, selector switch **SS1**, switch arm **R3a**, switch arm **R1a**, and jumper **80**. Energization of the solenoid **Va1** maintains the first point valve **Va** in sufficient open condition. In like manner, the end point valve **Vb** and its solenoid valve **Vb1** are energized through lines **72**, **74**, **78**, selector switch **SS2**, switch arm **R5b**, switch arm **ES1a**, switch arm **R1a**, and jumper **80**. The addition of water and mixing of the sand continues concurrently until the moisture content of the sand approaches a value near to but substantially below the final

required value. At this time the value of the capacitance of the moist sand as sensed by the moisture probe **26** is such that the various capacitances connected to the points **X**, **Y**, including the first point capacitance **62**, operate to cause the **6SN7** tube to oscillate, thereby establishing a current through the relay coil **M** sufficient to shift the contacts **M1** and **M2** to the left from the position shown.

Closure of the switch **M1** establishes a current through relay **R3**, switch arm **R1a**, and jumper **80**. Energization of relay **R3** moves switch arm **R3a** downwardly from the illustrated position, thus breaking the circuit through the solenoid **Va1** and closing the first point valve **Va**. Switch arm **R3a** completes a circuit through the relay **R3** and through the solenoid **82** of a switch having contacts indicated generally at **82a**. Energization of solenoid **82** moves switch contacts **82a** upwardly thus disconnecting the first point capacitance **62** and connecting the end point capacitance **64** and the bias capacitance **66** into the circuit. It will be observed that the circuit through relay **R3** is held closed by the relay **R3a** and hence from this time to the end of the cycle, relays **R1**, **R2** and **R3** remain closed.

In addition to the foregoing, energization of the relay **R3** shifts the switch arm **R3b** downwardly, thus preparing a circuit for subsequent energization of relay **R5**. This circuit extends from the switch arm **R4b** to contact **M2a**, contact **M2b**, switch arm **R3b**, switch arm **R1a**, and jumper **80**.

Since this first indication of adequate moisture was based upon control of the first point capacitance **62** and the temperature compensating capacitance **38**, subsequent passages of the rollers over the moisture probe will not result in indications of adequate moisture until a substantial additional quantity of water has been added. Ordinarily, it is preferred to add approximately 80% of the water while the first point valve **Va** remains open, the additional 20% being added at a much slower rate through the smaller end point valve **Vb**.

As soon as the scraper has removed the moist sand from the moisture probe following this first indication, relay coil **M** is de-energized and contacts **M1** and **M2** again return to the illustrated position to the right. At this time a circuit is completed through the normally closed switch arm **R5a**, contact **M2c**, contact **M2b**, switch arm **R3b**, switch arm **R1a**, and jumper **80**. Energization of the relay **R4** closes switch **R4a** establishing a holding circuit for the relay **R4** which keeps the relays **R4** and **R7** throughout the balance of the cycle. Energization of the relay **R7** opens normally closed contacts **R7a**, thus disconnecting bias capacitance **66** from the circuit and leaving the end point capacitance **64** in control. The operations are continuous without further change until there is a second indication of adequate moisture which as before, energizes the relay coil **M** and shifts the contacts **M1** and **M2** to the left. The contact **M1** has no further function since it has already energized relay **R3** which remains energized through a holding circuit for the balance of the cycle. However, movement of the switch arm **M2** to connect contacts **M2a** and **M2b** energizes relay **R5** through switch arm **R4b**, contacts **M2a**, **M2b**, switch arm **R3b**, switch arm **R1a**, and jumper **80**. Energization of the relay **R5** shifts switch arm **R5b** to the lower position, thus breaking the circuit to solenoid **Vb1** and closing the end point valve **Vb**. This would normally constitute the end of the cycle but additional provision is made for rechecking the moisture content a number of times to insure against premature termination of the cycle while the average moisture content of the sand is below that required.

The brief interval in which the switch arms **M1** and **M2** are to the left (before the next succeeding passage of the plow **24**) has closed the end point valve **Vb**, but downward movement of the switch arm **R5b** has established a circuit through the relay **R5** which includes

switch arm ES1a of a short interval timer ES1. Thus, as long as the switch arm ES1a remains closed, the relay R5 will remain energized and the end point valve Vb will remain closed. The motor of the timer ES1 is at this time energized through switch arm R5a, contacts M2c and M2b, switch arm R3b, switch arm R1a, and jumper 80. The timer ES1 may be set for an interval for example of three seconds and after three seconds the switch arm ES1a will open if the timer is permitted to run its course. However, during the three seconds in which the timer ES1 is timing out, there will be a subsequent sensing of moisture content and if the moisture content of the sand is adequate relay M is momentarily energized and switch arm M2 will interconnect contacts M2a and M2b briefly and then return to interconnect contacts M2b and M2c. This will have the effect of breaking the circuit to the motor of timer ES1 at the contact M2c and return of the switch arm M2 to the contact M2c will restart the timer for timing out the same interval. Thus, so long as the periodic moisture sensing operations sense adequate moisture, the timer will be automatically restarted so that the timer contact arm ES1a will never open and the relay R5 will remain energized through switch arm R5b, switch arm ES1a, switch arm R1a, and jumper 80. This will interrupt the circuit through solenoid Vb1 at switch arm R5b and the end point valve will remain closed. If however, passage of a roller 22 over the moisture probe gives a dry signal, there will be sufficient time for the timer ES1 to time out, causing opening of timer switch arm ES1a and breaking the circuit to the relay R5, thus restoring switch arm R5b to its illustrated position. This will complete the circuit through the solenoid Vb1 and reopen end point valve Vb. The end point valve Vb will remain open until a subsequent sensing of moisture content indicates the correct value thereof at which time the end point control valve will close and rechecking will resume. The timer motor ES1 is restarted and switch arm ES1a closed when relay R5 is next energized, by the next wet signal.

In order to terminate the cycle after a predetermined interval which may be devoted to rechecking, a longer interval timer ES2 is provided having contacts ES2a in a branch circuit connecting the relay R5 across the lines. Thus, when the switch arm ES2a is closed, the relay R5 remains energized, switch arm R5b remains in its lower position, thus interrupting the circuit to the solenoid Vb1, and finally terminating the cycle.

Initiation of the longer interval timer which finally terminates the cycle is initiated through normally closed switch arm R6a, relay R8, switch arm R5a, contact M2c, contact M2b, switch arm R3b, switch arm R1a, and jumper 80. Energization of relay R8 closes switch arm R8a, thus energizing relay R6 which in turn closes switch arm R6b, establishing a holding circuit through relay R6 and opening switch arm R6a. The continued energization of relay R6 and closure of switch arm R6b maintains the motor of timer ES2 energized for a predetermined interval upon the termination of which, timing out of the timer closes switch arm ES2a, thus establishing a circuit through relay R5 and moving switch arm R5b downwardly from the illustrated position to break the circuit to solenoid Vb1. This finally closes the end point control valve Vb if it was open at this time and marks the end of the cycle.

Referring now to Figure 2, the moisture probe is adapted to be mounted in the bottom wall 100 of the tank or mill 10. More specifically, the bottom wall 100 of the mill is provided with removable wear plates 102 and one of these is recessed as indicated at 104 to receive a flat cup-shaped element 106 which receives a flat plate 108 of a suitable di-electric plastic material, preferably polytetrafluoroethylene sold under the trade name Teflon. The plate 108 of plastic material is retained in the cup 106 by means of rivets 110 having relatively large cy-

lindrical heads 112. Centrally, the plate 108 is provided with a circular opening 114 which receives an assembly comprising a metallic thimble 116, details of which are best seen in Figure 3. The thimble 116 includes a cylindrical wall 118 which is relatively thin, a conical wall portion 120, and a cylindrical recess 122 the side walls of which are provided with openings 124 for the reception of a pin. The lower end of the thimble 116 has a tapped opening 126.

10 In the assembly, a Teflon button 128 is provided which is shaped to fit within the open end of the thimble 116 and it is retained therein by means of a pin extending through the openings 124 of the thimble and through the lower reduced portion of the button. Surrounding the 15 metal thimble 116 is a plastic sleeve 130 having an upper cylindrical portion to receive the cylindrical portion of the thimble, a conical portion therebetween, and an enlarged cylindrical opening which receives the lower portion of the thimble with clearance. The outer edge of 20 the sleeve 130 fills the opening 114. The upper surfaces of the heads 112 of the rivets, the plastic plate 108, the sleeve 114, the button 120, and the cylindrical portion 118 of the thimble are all coplanar and occupy the plane of the upper surface of the wear plate 102.

25 Rigidly connected to the thimble is an elongated center post 132, its upper end having a reduced threaded extension received in the tapped hole 126 provided at the lower end of the thimble. In order to retain the assembly in its lowermost position, an abutment ring 134 is provided in a tube 136 the upper end of which is welded to the bottom wall of the cup 106. Above the ring 134 is an indented groove indicated at 137 which forms an abutment against which the lower side of the ring 134 seats. Below the ring 134 is a plastic washer 138 having a downwardly extending reduced extension which receives a metallic abutment washer 140. The lower end of the center post 132 is threaded as indicated at 142 and carries a nut 144 which through a washer 146 supports a plastic washer 148. The plastic washer 148 has a reduced upper extension receiving a brass washer 150. Extending between the metal washers 140 and 150 and surrounding the center post is a compression spring 152. The spring urges the center post and hence the stainless steel thimble, the button and the sleeve downwardly and maintains them in accurately centered and seated relation against the respective conical supporting surfaces. The center post is provided with an elongated insulating sleeve 154 which prevents accidental engagement between the spring and the center post.

50 In order to maintain the metallic elements of the probe at a temperature at least as high as that of the sand within the mill, suitable electric heating means is associated with the structure, this means being diagrammatically indicated at 156.

At its lower end the tube 136 is connected to an angular conduit 160 which receives a coaxial cable diagrammatically indicated at 162. The lower end of the center post 132 is connected to the conductor of the coaxial cable through a resistor 164.

60 With the foregoing construction it will be observed that the space between the exposed edge of the stainless steel thimble and the nearest adjacent grounded metallic elements is determined by the spacing of the closest rivets 110 to the thimble. When this space is bridged by a 65 quantity of moist sand, the exact capacitance of the moist sand may be measured by the connection between the center post of the moisture probe and ground.

Inasmuch as the probe is exposed to sand in a mill which is subjected to a mixing action, the abrasive effect of the sand is to wear away the material exposed thereto. By employing cylindrical heads 112 on the rivets 110 and by forming the upper end of the thimble in the form of a cylindrical shell, it will be observed that a wearing away of the surface of the elements of the moisture probe by 75 the continued passage of sand thereover will not affect

the capacitance measurement dependent upon the moist sand surrounding the exposed end of the moisture probe.

It is desirable in the present probe to insure that a specimen of sand, having been compacted against the probe to give a reading of moisture content, may be removed in its entirety by the next passage of a scraping element in proximity to the surface of the probe. This is accomplished by employing tetrafluoroethylene as the resin from which the plate 108, button 128, and sleeve 130 are formed. Preferably, the plastic compound contains approximately 20% coke flour or graphite fill to produce surface characteristics facilitating separation of a compacted specimen of sand therefrom.

The drawings and the foregoing specification constitute a description of the improved end point moisture content control for sand in such full, clear, concise and exact terms as to enable any person skilled in the art to practice the invention, the scope of which is indicated by the appended claims.

What we claim as our invention is:

1. A mill for granular material, means including a valve for adding water to granular material in said mill during mixing, a solenoid connected to operate said valve, a relay connected to control said solenoid, a control circuit for said relay, a first condenser in a wall of said mill exposed to moist granular material in said mill the capacitance of which is a function of the moisture content of the moist granular material, a second condenser carried by said mill the capacitance of which is a function of its temperature, current control means in said control circuit sensitive to outside capacitance connected thereto, and means connecting said condensers to said current control means.

2. Structure as defined in claim 1 in which said current control means is a vacuum tube.

3. Apparatus for tempering granular material which

comprises a mixer for mixing granular material and water, means for adding water to the granular material including a shut-off valve, a variable moisture responsive electrical impedance exposed to moist granular material in said mixer, a variable temperature responsive electrical impedance responsive to temperature of the granular material in said mixer, means electrically connected to said moisture and temperature responsive impedances operable to establish a resultant electrical impedance dependent upon the value of the moisture content and temperature of the granular material, a solenoid connected to said shut-off valve for actuating said valve, and a control circuit including said resultant impedance connected to said solenoid and operable to actuate said solenoid to close said valve upon attainment of a predetermined resultant electrical impedance.

4. Apparatus as defined in claim 3 in which said moisture and temperature responsive impedances are variable capacitances.

20 5. Apparatus as defined in claim 3 in which the control circuit comprises a relay in control of said solenoid, a vacuum tube connected to said relay, and means connecting said resultant impedance to said vacuum tube to control said tube.

25 6. Apparatus as defined in claim 3 in which said temperature responsive impedance is positioned to be continuously responsive to temperature of the granular material in said mixer.
